DESIGN FOR A VENDING MACHINE CABINET

Christian Gabrielsen, Belleville, N. J., assignor to Rowe Manufacturing Co., Inc., New York, N. Y., a corporation of New York

Application May 16, 1939, Serial No. 85,017

Term of patent 7 years

To all whom it may concern:

Be it known that I, Christian Gabrielsen, a citizen of the United States, residing at Belleville, county of Essex, State of New Jersey, have invented a new, original, and ornamental Design for a Vending Machine Cabinet, of which the following is a specification, reference being had to the accompanying drawing, forming a part thereof, in which Fig. 1 is a perspective view of a vending machine cabinet showing my new design, and Figs. 2 and 3 are respectively a side elevation and a plan view both on reduced scale of the said cabinet.

I claim:

The ornamental design for a vending machine cabinet, as shown.

CHRISTIAN GABRIELSEN.
